UNITED STATES PATENT OFFICE.

HIRAM Q. HOOD, OF CARTHAGE, MISSOURI, ASSIGNOR TO EZRA T. HARDAWAY, BENJAMIN F. BARNHART, GEORGE W. BARNHART, AND CHARLES FRENCH, OF SAME PLACE.

STOVE.

SPECIFICATION forming part of Letters Patent No. 669,582, dated March 12, 1901.

Application filed January 28, 1899. Serial No. 703,708. (No model.)

To all whom it may concern:

Be it known that I, HIRAM Q. HOOD, a citizen of the United States, residing at Carthage, in the county of Jasper and State of Missouri, 5 have invented a new and useful Stove, of which the following is a specification.

This invention relates to stoves; and the object of the invention is to provide a simple and compact device of this character in which 10 coal and wood can be used with equal facility to obtain good results.

My invention relates especially to the construction of the fire-box and the grate; and it consists in the peculiar construction and 15 arrangement of devices hereinafter fully set forth, and pointed out in the claim.

In the accompanying drawings, Figure 1 is a vertical longitudinal sectional view of a stove embodying my improvements. Fig. 2 20 is a vertical transverse sectional view of the same, taken through the fire-box. Fig. 3 is a detail perspective view of the wood-burning grate.

Referring to the drawings, 2 designates the 25 bottom plate of the stove, to which the side plates 3 and 4 and the end plates 5 and 6 are secured to form a substantially rectangular body, which is covered by the top plate 7, having a series of filling-openings, as 8, covered by the caps or lids 9, said parts usually 30 being cast and being detachably united to the legs or other supports 10.

The stove has at the front side thereof the usual fire pot or chamber 12, of which the 35 grate constitutes the floor, and beneath which the ash-pit 13 is disposed, and into which latter ashes and other refuse from the fire-pot 12 can be dumped or discharged at proper intervals.

40 The side plate 3 carries a supply-chute, as 14, leading into the fire-pot 12 and normally closed by the cover 15, hinged to the top plate 7 and which is lifted to introduce coal into the fire, although the coal of course may be furnished by lifting the caps 9 over the fire-pot.

45 The oven is designated by 20, and it is shown as being in the form of a cylinder lying transversely across the stove.

The stove is furnished near the upper rear 50 side with a collar 30, surrounding the exit-

opening 31 and over which the smoke-pipe 32 is adapted to fit.

In conjunction with the oven I provide a damper, which is located in proximity to the exit-opening 31, the damper being designated 55 by 33.

The end and top plates 6 and 7, respectively, are provided on their inner sides with ledges or flanges 36 37, extending entirely across the stove adjacent to the exit-opening 60 31 and which are adapted to be engaged by the edge of the damper when it is in its two positions. The fire being in the fire-box and the damper being in a substantially vertical position and in contact with the ledge 37, the 65 heated air will fill the space between the upper side of the oven 20 and the top plate 7 up to the damper and the space around the under and far sides of the opening up to the opposite face of the damper, thereby thoroughly and uniformly heating the oven. To promote the draft of the stove, the damper 70 will be thrown down into contact with the ledge 36, so that the heated air does not pass around the oven, but simply passes directly 75 from the fire-box to and through the exit-opening 31 and into the smoke-pipe 32.

For the purpose of preventing the application of undue heat to the oven near the fire-box a guard, as 40, is disposed between the 80 oven and the fire-box, said guard being shaped to correspond with the form of the oven and consisting, as will be evident, of an arc-shaped plate extending entirely across the stove and located a short distance from the periphery 85 of the oven, so as to permit the circulation of the heated air between said parts.

No claim is made herein to the peculiarities in the construction of the stove hereinbefore referred to, nor are the same more particularly described herein, as they are described and claimed in a divisional application for Letters Patent of the United States, No. 8,197, filed by me March 10, 1900, and allowed June 22, 1900. 90

The fire-box of the stove is provided with integral inwardly-extending flanges 44 in its side and one of its end walls and has an opening 43 in the other end wall corresponding with the front side of the stove, the lower side 100

of which opening is on the same level as the upper sides of said flanges. The bricks are supported on the said flanges, as shown, and said flanges extend inward beyond the bricks 5 and serve also to support the grate.

The grate 41 comprises a pan and has side walls *a* and one end wall *b* bearing against the inner sides of said bricks, and the outer end of the grate extends through the opening 10 43 and has the plate *c* bearing against the front side of the stove and closing said opening, and on said plate is a suitable handle.

It will be understood that the grate may be withdrawn from the fire-box through the said 15 opening 43. The side and end walls of the grate prevent the overflow of ashes therefrom when the grate is removed from the stove. The bottom of the grate may be perforated, as at *d* in Figs. 1 and 2, when coal is used as the 20 fuel or may be imperforate, as at *e*, Fig. 3, when wood is used as the fuel.

Having described my invention, what I claim is—

A stove having a fire-box provided with in-

tegral inwardly-extending flanges in its side 25 and one of its end walls, and having an opening in the other end wall the lower side of which is on the same level as the upper sides of said flanges, the bricks supported on the said flanges, and the grate, also supported on 30 the said flanges, which extends inward beyond the said bricks, the said grate comprising a pan and having side walls and one end wall bearing against the inner sides of said bricks, the outer end of said grate extending 35 through the opening in one of the end walls of the fire-box and having the plate bearing against the outer side thereof, when said grate is pushed in, the said grate being adapted to be withdrawn from the said fire-box through 40 the said opening, substantially as described.

In testimony that I claim the foregoing as my own I have hereto affixed my signature in the presence of two witnesses.

HIRAM Q. HOOD.
